UNITED STATES PATENT OFFICE.

BRADFORD A. RUGG AND EZRA H. BENJAMIN, OF OAK HILL, NEW YORK.

MACHINE FOR FEEDING PAPER TO PRINTING-PRESSES.

Specification of Letters Patent No. 11,653, dated September 5, 1854.

To all whom it may concern:

Be it known that we, BRADFORD A. RUGG and EZRA H. BENJAMIN, of Oak Hill, in the county of Greene and State of New York, 5 have invented a new and useful Improvement in Paper-Feeding Machines for Printing-Presses.

The nature of our invention consists in providing a series of rollers and endless 10 aprons so arranged that by placing the paper between the aprons the sheets shall be separated and delivered, one by one, into the printing-press, with as much rapidity as desired.

15 To enable others skilled in the art to make and use our invention, we will proceed to describe its construction and operation, reference being had to the annexed drawings forming a part of this specification, in 20 which,

Figure 1, is a side sectional view of our improvements; Fig. 2, a side view; Fig. 3, portion of a side section of the upper part; Fig. 4, section showing the upper part open 25 to receive the paper.

Similar letters refer to like parts.

A, frame of the machine; B, upper portion of same; a, b, printing-cylinder; a' b', cog-wheels on same; a² b², springs; c, d, e, 30 f, i, k, l, m, n, apron-rollers; c', intermediate wheel; d', pivot; g, h, aprons; i', ratchet wheel; i², friction wheel; k', slot; o, drop-board; o', extension rod of same; p, sliding bar; q, lifting-piece; s, cam shaft; s' s'', 35 cams; t, lifting lever; t', pivot of same; u, paper box; v, connecting-rod; w, connecting-lever; w', pivot of same; x, ratchet bar; y, rack; z, lifting bar.

It is well known that if we place a number 40 of sheets of paper together in a pile, one above the other, and roll them at one edge, the act of rolling alters the position of the sheets, causing one to overlap the other. We take advantage of this fact in our machine 45 by providing a series of rollers and aprons, by means of which we roll the sheets and cause them to overlap each other as far as required for feeding regularly into the printing press.

50 The upper part of the frame of the machine, B, turns upon a pivot, d', and when the paper for printing is to be placed in the machine, the upper frame, B, and all the parts thereto attached are thrown up, and 55 the paper placed within the paper-box, u,

and upon the apron, h, as seen in Fig. 4, where the colored lines indicate the paper. The lower apron, h, moves in the direction of arrows, 1, and extends around the rollers, i, k, l, m, n. The upper apron, g, moves in 60 the direction of arrows, 2, and extends around the rollers, c, d, e, f.

k, is a weighted drop-roller which slides up and down, being guided by the slot, k'. The object of this drop-roller is to keep the 65 apron, h, in constant tension. When there is no paper between, this apron comes in contact with the other apron at, d, as seen in Figs. 3 and 4. When the sheets are passing around, d, the weighted roller, k, rises, and 70 the apron, h, expands so as to accommodate itself to the thickness of the sheets between. The speed of both aprons is the same. The tension of apron, h, is, also, the same, being 75 always regulated by the weighted roller, k.

The machine is put in motion by means of the printing-cylinder, b, the teeth of which mesh with those on the wheel, x. Upon the shaft, s, there are two cams, s', s''. The round cam, s'', has a connecting-rod, v, one 80 end of which is fastened to the lower part of the lever, w, which has a center at w'. To the upper part of, w, the ratchet bar, x, is attached. The lever, w, being put in motion the ratchet-bar, x, acts upon the ratchet 85 wheel i', and gives an alternate movement to the apron-roller, i, to which the ratchet is attached. For every revolution of, x, the wheel, i', is advanced one or more cogs. The length of the stroke of the ratchet-bar, x, is 90 adjustable, as seen in Fig. 2. The motion of, i, causes the apron, h, to move in the direction of arrows, 1, and with it the other rollers with which the apron is connected, viz, l, m, n. Upon the opposite end of, i, there is 95 a friction pulley, i², which imparts motion to pulley c' upon the roller, c. Thus the motion of rollers, c and, i, is the same, and, also, the aprons, g, and, h. The sheets to be fed into the press, having been placed upon the lower apron, h, with their ends resting in the paper-box, u, as seen in Fig. 4, the upper 100 frame, B, with its apron and rollers is shut down, and the machine started. The apron, h, carries the pile of papers up its incline 105 until the pile comes in contact with apron, g, and roller, d. The apron, h, now expands in the manner before described, and the sheets bend around the roller, d, and emerge from between the two aprons, upon the top 110

of apron, g , along which they are carried beneath the drop-board, o , toward the printing cylinders.

In bending around the roller, d , the sheets 5 become overlapped, the operation being assisted by the constant attrition of the belt, h , upon the pile of paper. It should be observed that by the act of passing around the roller, d , the position of the paper is 10 altered. The top sheet, when the paper lay upon the belt, h , becomes the bottom sheet when the paper has arrived upon the top of apron, g . The sheets having passed around roller, d , and under drop-board, o , 15 now approach the printing cylinders, a , b , and the top sheet which overlaps or projects beyond those beneath, is seized by the springs ($a^2 b^2 Q$) of the printing cylinders and drawn into the type.

20 The apron, g , and, with it, the paper upon its top, is advanced toward the printing cylinder, one notch for every revolution of the wheel, z , or just in time to present a new sheet to the springs, a^2 , b^2 , of 25 the printing-cylinder, after the top one has been taken. Fig. 3, shows the manner in which the sheets are presented to the printing-cylinders.

In feeding sheets into the printing press 30 it is necessary to have some means of freeing the upper sheet while those underneath are detained; otherwise more than one sheet would be drawn into the press at a time. This is accomplished by means of the drop-board, o , which is made to rise and fall alternately with the forward movement of 35 the sheets, permitting the upper sheet to go free, but falling upon the latter end of the sheet next below, detaining it and all 40 beneath, while the upper sheet is being drawn into the press. The proper alternating motion of, o , is obtained by means of the downward extension-rod, o' , which is 45 attached to, o . This extension-rod touches upon the top of the lifting-piece, q . The lifting-piece, q , is raised by the lever, t ,

having a center, t' , the opposite end being operated by the cam s' ; the lifting-piece, q , is thus raised, and with it the drop-board, o . The drop-board, o , is easily adjusted to 50 different lengths of paper, by means of the horizontal sliding bar, p , to which the drop board is attached. The bar, p , has a rack at one end the teeth of which mesh with a cog-wheel, e , having on the opposite end of 55 the shaft a hand pulley e' . The lifting-piece, q , is elongated at its upper end, in order that the drop-board, o , shall operate at whatever horizontal position it has been adjusted. At, z , there is a hand-lifting bar 60 for convenience in raising the drop-board by hand whenever desired.

Our machine possesses many advantages over any other apparatus for the same purpose yet made, being simple, effective, and 65 cheap. The manner in which the sheets are made to overlap and feed into the press, very closely resembles the operation of feeding by hand. It is immaterial whether the paper is dry or damped in passing through our 70 machine.

Having thus described our invention we claim—

1. The combination of one or more endless aprons in such a manner that the sheets 75 of paper in approaching the printing cylinders shall be rolled around a roller, and thus caused to overlap each other, the arrangement and combination of respective parts by which this overlapping is produced, being, substantially, the same as herein set forth.

2. We claim the combination of the dropping-board, o , operated as described, with the apron, g , in the manner and for the purposes substantially as herein set forth.

BRADFORD A. RUGG.
EZRA H. BENJAMIN.
